LIFT

Joseph A. Schwab, Albany, N. Y.

Application October 29, 1943, Serial No. 508,262

1 Claim. (Cl. 255—51)

This invention relates to a lift especially adapted for supporting and varying the elevation of a power drill employed in drilling bridge abutments, sea walls and other structures, wherein the tide of the body of water must be considered.

The primary object of the invention is the provision of a device of the above stated character which when mounted on a float, barge or the like may be conveniently operated, either manually or by motor power to raise or lower the drill carried thereby for compensating for the rise and fall of the tide, to maintain the drill bit aligned with the hole being drilled to prevent the drill bit from binding or sticking or from breaking incident thereto.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating a drill lift constructed in accordance with my invention and showing the mounting thereof on a barge or float for supporting the bit of the drill in alignment with the hole being drilled in a bridge abutment, sea wall or the like.

Figure 2 is a plan view, partly in section, illustrating the same.

Figure 3 is a fragmentary vertical sectional view showing a portion of the lift.

Figure 4 is a fragmentary horizontal sectional view showing both the hand and power means for bringing about vertical adjustment of the drill.

Figure 5 is a fragmentary side elevation, partly in section, of the operating means.

Referring in detail to the drawings, the numeral 5 indicates a barge or float and 6 a bridge abutment, sea wall or the like, and 7 holes in the bridge abutment or sea wall formed by a power operated drill 8 of a conventional construction either pneumatically or electrically operated. Heretofore it has been very difficult to maintain the bit of the drill 8 properly aligned with the hole being drilled due to the constant changing of the tide, frequently resulting in the bit sticking or jamming in the hole and sometimes resulting in the breaking of the bit. To overcome this difficulty, the present invention is employed for the support of the drill on the barge or float whereby vertical adjustment of the drill can be

easily brought about and further whereby the drill may be adjusted horizontally.

Mounted vertically on the barge or float is a tubular post 9, the lower end of which is fitted in a base 10 removably secured to the barge or float.

Paralleling the post 9 and forming an integral part with opposite sides thereof are guide ribs 10' to prevent turning of a bearing sleeve 11 slidably mounted on the post. The bearing sleeve 11 includes a clamp 12 for supporting horizontally of the post and between the latter and the bridge abutment or sea wall a bar 13. The clamp 12 will permit the bar 13 to be adjusted endwise and mounted thereon is the drill 8, the latter being provided with a clamp 14 to embrace the bar 13. By employing bars 13 of different lengths one or more drills may be mounted thereon. The clamp 14 will permit the drill 8 to be tilted 15 upwardly or downwardly for varying the direction of operation of the bit of the drill indicated by the character 15.

A vertically arranged frame 16 is carried by the base 10 and the upper portion of the post 9 and rotatably supports a feed shaft 17. Meshing with the feed threads and forming an integral part of the bearing sleeve 11 is a feed nut 18. The rotation of the feed shaft 17 in different directions brings about sliding movement of the

bearing sleeve in opposite directions and consequently raises and lowers the drill and its bit with respect to the bridge abutment or sea wall. The upper end of the feed shaft has secured thereto a gear 19 engaged by gears 20 and 21.

35 A power shaft 22 is secured to the gear 20 and a hand operated shaft 23 is secured to the gear 21. The hand shaft 23 is journaled in the upper portion of the post 9 and is equipped with a hand wheel 24. The shaft 22 is journaled in a frame

40 25 carried by the upper portion of the post and is connected to a motor 26 of the reversible type, either electrically or pneumatically operated. The motor 26 is supported by the frame 25. Through the use of the motor 26, the drill 8 may 45 be raised and lowered by power and at any time it is desired to vary the elevation of the drill 8 by hand the hand wheel 24 may be rotated.

Thus it will be seen that a very efficient lift has been provided for the support of a drill of the power type which can be easily raised and lowered to align the bit thereof with the hole being drilled to prevent the bit from binding or jamming in the hole due to the constant changing of the tide.

55 Braces 29 may be connected to the upper end

of the post 9 and to the barge to cooperate with the base 10 in maintaining the post 9 in a vertical or perpendicular position.

While I have shown and described the preferred embodiment of my invention, it will be understood that minor changes in construction, combination and arrangement of parts may be made without departing from the spirit and scope of the invention as claimed.

Having thus described my invention, what I claim is:

In a lift, a vertically arranged post, a base attaching the lower end of the post to a supporting structure, a bearing sleeve mounted on the post for free sliding movement thereon, means carried by the post and engaging said bearing sleeve for preventing rotation of said bearing sleeve relative to the post, a vertical frame par-

allel to said post and having its lower end secured to said base with its upper end secured to said post, a feed screw journalled through the upper end of said frame with its lower end secured in the lower end of said frame, said feed screw paralleling said post between said frame and said post, a feed nut engaging said feed screw and secured to said bearing sleeve, means for rotating the feed screw, a clamping member secured to said bearing sleeve for adjustably carrying and positioning a horizontal supporting bar and a horizontal frame carrying a drill adjustably clamped to said supporting bar at right angles thereto, whereby said horizontal frame may be supported at varying vertical angles relative to said supporting bar.
